UNITED STATES PATENT OFFICE.

JOHN HEWES, OF LEICESTER, ENGLAND.

CREMATOR OR APPARATUS FOR BURNING REFUSE.

SPECIFICATION forming part of Letters Patent No. 371,842, dated October 18, 1887.

Application filed March 16, 1886. Serial No. 195,391. (No model.)

To all whom it may concern:

Be it known that I, JOHN HEWES, a subject of the Queen of England, residing at Leicester, in England, have invented an Improved Cremator or Apparatus for Burning Refuse, of which the following is a specification.

In the accompanying drawings, Figure 1 is an elevation of a cremator, a portion of which is removed to show the internal arrangement. Fig. 2 is a section of the cremator through the center of the furnace.

The invention relates to furnaces or apparatus designed to incinerate refuse matter, such as house-garbage, sewage, &c.; and it has for its object an apparatus of simple construction and provided with means for utilizing the gases evolved during the process of incineration.

The invention consists in the construction of the furnace and the combination of elements therein, substantially as hereinafter described, and as set forth in the claims.

In practice I prefer to support the incinerator or cremator from pillars A' or other suitable support at such an elevation as to afford the necessary space for a vehicle of any sort to be run under the retorts to receive the incinerated or burned material therefrom, as shown in the drawings.

The inclosing-walls of the apparatus may be constructed of any suitable material—as, for instance, metal—and provided with a lining, B, of fire-brick.

Iron or other pipes or retorts C pass vertically through the chambers of the apparatus, the opposite ends of which are supplied with lids or valves D and D', which may be unscrewed or otherwise detached to allow of sewage and other substances being introduced into the said pipes, and after treatment of being emptied into a suitable vehicle or receptacle for removal.

The gas generated in the retorts C is conducted through the small pipes E to the pipe F, which is continued down to the combustion-chamber at F', into which the said gas is discharged. Suitable union cocks or valves, G, may be employed to regulate or shut off the supply of gas when desired.

The heated air or gas and other products contained in the combustion-chamber L are conveyed by the bell-mouthed pipes I under-

neath the furnace-grate, and thence pass through the grate-bars to the fire, where they may be consumed and thereby assist to sustain the fire; or, if desired, the gas may be conveyed by pipes to a gasometer or other suitable retort, where it may be stored for use for any desired purposes.

In practice I divide the combustion-chamber into two chambers, L and L', by means of a partition or baffle plate, K, provided with openings K', of greater diameter than the retorts, through which said retorts extend, as shown, and so as to provide passages for the heat to pass into the upper chamber.

A chimney, A, in communication with the upper chamber, L', is arranged at any convenient point of the apparatus to produce the necessary draft.

Q is the furnace, the heat from which passes through the opening in the fire-square K' to the chamber above, and R is a suitable rod, which operates the valves S in the pipes I to regulate the supply of hot air or gases to the furnace.

The described construction may be varied in many ways. The retorts C, for instance, may be arranged horizontally within the combustion chamber or chambers, and a perforated pipe or pipes may be arranged in the upper combustion-chamber, L', and connected with the pipes F, so that a portion of the gas generated in the retorts may be utilized as fuel in said upper chamber to heat the upper portion of the retorts. This latter arrangement is especially desirable in large apparatus.

Having now described my invention, what I claim is—

1. In an apparatus for treating organic matter, a furnace and a combustion-chamber in communication therewith, in combination with a series of retorts provided with charging and discharging valves, said retorts extending through the combustion-chamber and having their charging and discharging ends located outside thereof, and a gas-pipe common to all the retorts connected thereto, whereby the gases generated in the retorts are carried to the combustion-chamber for use as fuel, substantially as and for the purposes specified.

2. In an apparatus for treating organic matter, a furnace, a combustion-chamber communicating with said furnace, and a heating-

chamber communicating with the combustion-chamber, in combination with a plurality of retorts extending through the heating and combustion chambers and having their charging and discharging ends outside of said chambers, and a gas-pipe common to all the retorts and connected therewith outside of the chamber and communicating with the combustion-chamber, substantially as and for the purposes specified.

3. In an apparatus for treating organic matter, the combination of a furnace, a superposed combustion-chamber communicating therewith, and a heating-chamber located above the combustion-chamber, of a plurality of vertical retorts extending through the chambers and having their upper charging and lower discharging ends located above and below said chambers, respectively, said retorts passing

through openings in the partition-wall between the heating and combustion chambers, which openings are of greater diameter than the retorts, a gas-pipe common to all the retorts and connected to the charging end thereof and communicating with the combustion-chamber, and a gas-pipe communicating with the latter chamber and the furnace, substantially as and for the purposes specified.

In testimony whereof I have hereunto set my hand in the presence of the two subscribing witnesses.

JOHN HEWES.
